UNITED STATES PATENT OFFICE

IVAN E. DAY, OF EDGERTON, OHIO

CAR SEAL

Application filed May 17, 1929. Serial No. 363,848.

This invention relates to improvements in seals of that type applicable to car doors and other closures, the purpose of which is to prevent unauthorized opening thereof. The object of the invention is to provide an inexpensive expedient for sealing closures, which may be readily applied and which may not be removed without mutilation.

This object is accomplished by the construction illustrated in the accompanying drawings, in which:

Fig. 1 is a perspective view of the seal in locked position;

Fig. 2 is a diagram showing the shape of a formed metallic plate from which the seal is made;

Fig. 3 is a side elevation of a seal embodying the invention, partly in section as it appears before being locked; and

Fig. 4 is a similar view of the seal after having been locked.

The invention is comprised of a seal formed of a thin metallic plate 1, initially shaped as indicated in Fig. 2, to have a main portion 2 with oppositely disposed seam flanges 3 and 4, at the sides thereof, and oppositely disposed lock-members 5 and 6 at the ends thereof, and also contiguous with one end thereof a strip 7 to form a shackle. The lock member 5 has a portion thereof cut and bent so as to form a projection 8, and the lock member 6 also has portions thereof cut and bent to form a series of projecting latches 9, the end of said lock member 6 being slit and bent so as to present divergent fingers 10 and 11.

The free end of the strip 7 has made therein at a point spaced from its extreme end a slot 12, and in that portion of the strip back of the opening is formed a series of projecting latches 13 that slant backwardly from said end. Also, the strip has a deflector 14 in the form of a tongue that projects outwardly from the face of the strip oppositely with respect to the latches 13, and toward the slot.

The head 15 of the seal is formed of the main portion 2 and lock members 5 and 6 by folding the lock member 6 over onto the face of the main portion adjacent thereto and bending the lock member 5 so as to extend over the other lock member 6, and subse-

quently the main portion 2 is folded and its flanges 3 and 4 clinched together to form a seam 16, whereby the lock members 5 and 6 are enclosed by said main portion, the outer end of the head being closed by that part 55 of the lock member 5 adjacent said main portion. The rear end of the head is open for the reception of the free end of the shackle 7, the lock members 5 and 6 being spaced apart sufficiently to admit of the forced insertion of said end of the shackle therebetween. The fingers 10 on the free end of the lock member 6 extend downwardly and bear upon the adjacent face of the main portion 2 so that said lock member is held slightly 60 spaced between its ends from said face so as to admit of being sprung downwardly. The projection 8 on the lock member 5 is inclined downwardly at a point opposite the forwardly extending finger 11 of the lock member 6, and the latches 9 of the lock member 6 project upwardly and toward the closed end 65 of the head. When the shackle 7 is bent into a loop and its free end thereby presented for insertion into the open end of the head, the latches 13 thereof project downwardly and slant oppositely with respect to the latches 9 of the lock member 6, and the deflector 14 projects upwardly and toward the free end 70 of the shackle.

In applying the seal to a door fastening (not shown) or other object to be sealed, the shackle is looped through the fastening in the customary manner, and the end of the shackle is then inserted into the head between the lock members 5 and 6, whereupon the extreme end of the shackle is guided downwardly beyond the projecting finger 11 by the projection 8, causing the finger to become locked in the slot 12 of the shackle, 80 and the latches 13 of the shackle have locked engagement with the latches 9 of the lock member 6. Also, the deflector 14 is wedged between the end of the lock member 5 and the overlying wall of the head 15 formed of the main portion 2, as indicated in Fig. 4. The insertion of the deflector into place forces the end of the lock member downwardly so that the corresponding end of the head becomes closed. The deflector prevents 85 90 95 100

the insertion of a thin instrument into the head between the lock member 5 and the locked end of the shackle and thus forestalls unlawful opening of the seal.

What I claim is:—

- 5 1. A car seal formed of a single metallic sheet shaped with a main portion having side seam flanges and oppositely projecting lock members at its ends, and a shackle strip contiguous with one of its ends, one of said lock members having a projection formed therein, and the other lock member having divergent fingers at its free end and a series of projecting latches between its ends, the 10 free end of said shackle strip having a slot adjacent its extreme end, and a series of projecting latches back of said slot inclined therefrom, and a deflector back of said latches upon the side of the strip opposite thereto, said lock members being folded one over the other and inclosed by said main portion which is folded and its flanges clinched together forming a head for the seal, the free end of said shackle strip, 15 when inserted in said head, having locking engagement with one of said members, and the deflector thereof being wedged between the other member and the adjacent wall of said head.
- 20 2. A car seal formed of a single metallic sheet the main portion of which is folded and its sides clinched together to form a head, there being a lock member contiguous with each end of said portion that extend into said head, the one overlapping the other, and a shackle strip contiguous with one end of said head, its free end having latches, and a deflector formed therein that projects from opposite sides thereof, the end 25 of said strip being insertable in one end of said head, so as to have locking engagement with one of said members, said deflector being wedged between the other of said members and the adjacent wall of said head when 30 the end of said strip is locked in place whereby the corresponding end of said head is closed.
- 35 3. A car seal formed of sheet metal, provided with a head containing two oppositely disposed lock members contiguous with the corresponding ends of the head; and a shackle strip extending from one end of the head, one end of said strip being insertable between said members and having latches 40 on one side and a deflector on the opposite side thereof whereby the shackle strip is locked in the head and the end of the head through which the strip is inserted is closed.
- 45 4. A seal made of sheet metal, provided with a folded main portion and two lock members that are contiguous respectively with the opposite ends of said portion and are enclosed by said portion, which folded portion and members constitute a head, and 50 a shackle strip contiguous with one end of

the head, one end of said strip being provided with means engageable with both of said members within said head when inserted therein, for locking the strip and for closing the end of the head through which it is inserted.

In testimony whereof I affix my signature.
